CENTRIFUGAL COMPRESSOR
 Wilfred J. Lee, East Syracuse, N.Y., assignor to
 Belson Corporation, New York, N.Y.
 Filed Mar. 29, 1965, Ser. No. 443,335
 10 Claims. (Cl. 230—115)

The present invention relates to centrifugal machines such as compressors and exhausters and more particularly to an anti-surging control device for such machines.

It is well known in the art of centrifugal compressors and exhausters that under certain operating conditions of the machine the medium being handled will surge or pulsate violently in the compressor system. Such surging occurs under different operating conditions for different machines in accordance with their particular design. In general, however, surging occurs at a high outlet pressure and low inlet volume. As the machine is doing a minimum amount of work under these conditions, the power required to operate the machine and the rate of flow through both the inlet and outlet is at a minimum.

Such surging is undesirable, and devices have heretofore been provided to prevent surging. Such prior anti-surging devices usually comprise a throttling valve in the inlet to the machine to restrict flow thereto and thereby maintain stable operation. For example, the throttling valve may be operated by the pressure produced at the outlet of the compressor to move the valve to some equilibrium position where the flow to the machine is restricted sufficiently to prevent sudden surging of the medium being handled. As a result, the compressor operates at reduced efficiency because of the continuous throttling effect produced by the anti-surge valve at all operating flow rates. This reduced efficiency and pressure drop across the throttling valve of such anti-surging control devices, therefore, will occur below as well as above the critical operating conditions at which surging is apt to start.

One of the objects of the present invention is to provide an anti-surging control device for a centrifugal machine which permits operation of the machine at maximum efficiency until it approaches a critical condition at which surging may occur.

Another object is to provide an anti-surging control device of the type indicated which is brought into operation automatically in response to an operating condition of the compressor which may produce surging.

Another object is to provide an anti-surging control device of the type indicated which is adapted for use when the machine operates as an exhauster as well as when it operates as a compressor.

Still another object is to provide an anti-surging control device of the type indicated which is of relatively simple and compact construction, economical to manufacture and one which is reliable in operation in performing its intended function.

These and other objects will become more apparent from the following description and drawings in which like reference characters denote like parts throughout the several views. It is to be expressly understood, however, that the drawings are for the purpose of illustration only and are not a definition of the limits of the invention, reference being had for this purpose to the appended claims.

In the drawings:

FIGURE 1 is a side elevational view of an electric motor driven centrifugal compressor incorporating the novel anti-surging control device of the present invention and showing the current responsive relay for bringing the device into and out of operation;

FIGURE 2 is an enlarged view of the anti-surging con-

2

trol device, partly in section, and showing the relationship of the parts during stable operating conditions;

FIGURE 3 is a view similar to FIGURE 2 showing the relationship of the parts to throttle flow through the machine under operating conditions when surging is apt to occur.

FIGURE 4 is a sectional plan view taken on line 4—4 of FIGURE 3 to show the butterfly throttling valve in detail; and

FIGURE 5 is a view similar to FIGURE 1 showing the anti-surging control device applied to an exhauster and the flow operated vane type switch for starting and stopping its operation.

In the drawings, FIGURE 1 illustrates a centrifugal machine 6 to which the anti-surging control device 7 of the present invention is shown applied. In the illustrated embodiment, the centrifugal machine is of a conventional design and operating as a compressor having an inlet 8 and an outlet 9. The inlet 8 and outlet 9 comprise ports in the casing and pipes connected thereto and for purposes of description these elements will be referred to generally as the inlet and outlet. The centrifugal compressor 6 is driven by an electric motor 10 to which the current is supplied through the power lines P-1, P-2 and P-3.

The anti-surging control device of the present invention is illustrated in FIGURES 1 to 5 of the drawings as comprising a butterfly valve 11 having separate vanes 12 and 13 pivotally mounted for rocking movement on a common axis across the inlet 8. As shown most clearly in FIGURE 4 the vanes 12 and 13 are of generally hemispherical shape and each has sleeve sections 15 and 16, respectively, which interleave with each other on a shaft 17 to form a piano hinge. One end 17a of the shaft 17 and the sleeve section 15 at the opposite end of the shaft are journaled in bearings 18 and 19 at opposite sides of the inlet 8. The sleeve sections 16 and 16a of the vane 13 are rigidly attached to shaft 17 by means of pins 20 and 21 for rotation therewith and sleeve sections 15 and 15a of vane 12 rotate on the shaft. Ends 17b of the shaft 17 connected to vane 13 and 15b of the sleeve section 15 on the vane 12 extend through and beyond the bearing 19 for different distances and have radially extending arms 25 and 26 thereon. Operating arm 25 has a hub 27 clamped to the extended end 15b of the sleeve and arm extends radially from the sleeve at the opposite side of the shaft from its vane 12. Arm 26 also has a hub 28 clamped to the extended end 17b of the shaft 17 at the opposite side of the shaft from its vane 13. Sleeve section 15a of the vane 12 remote from the bearing 19 has a roller bearing 29 surrounding the shaft 17 to support the free end of the vane. Thus, rocking movement of the arms 25 and 26 downwardly from the position illustrated in FIGURE 2 to that illustrated in FIGURE 3 actuates the vanes 12 and 13 from a parallel back to back relationship at the center of the inlet 8 where they present a minimum resistance to flow to an extended relationship across the inlet to resist flow.

The vanes 12 and 13 are operated simultaneously by a fluid motor 30 having a cylinder 31 and piston 32 therein. A piston rod 33 extending through one end of the cylinder 31 is connected to a cross head 34. Cross head 34 is in the form of a yoke having depending legs 35 and 36 and the lower ends of the legs are connected to the outer ends of the operating arms 25 and 26 and the vanes 12 and 13 by adjustable links 37 and 38. Thus, when fluid pressure is supplied to the top of the piston 32 as viewed in FIGURE 2, it moves the piston rod 33 and cross head 34 downwardly and acting through the links 37, 38 and arms 25, 26 rocks the vanes 12 and 13 outwardly away from each other and across the inlet 8.

In accordance with the present invention the fluid

motor is rendered operative to actuate vanes 12 and 13 to a regulating position only when a condition exists which will produce surging. To this end, a loop circuit is provided having conduits 39 and 40 connected to the ends of the cylinder 31 at opposite sides of the piston 32 and a conduit 41 connecting conduits 39 and 40 to each other. The conduits 39 and 41 also includes the lower end of cylinder 42 of a piston valve 43 as will be observed by reference to FIGURE 2. The cylinder 42 has seats 44 and 45 at opposite sides of piston valve 43 at the upper and lower ends thereof. Fluid pressure is supplied through a conduit 46 and cylinder 42 of piston valve 43 onto the top of the motor piston 32 of the fluid motor 30 when the piston valve 43 is in its lowermost position engaging the seat 45; and the flow of motive fluid to the fluid motor is shut off when the piston valve is moved to its raised position to engage the seat 44. The motive fluid for operating the fluid motor 30 may be supplied from any source, but preferably the conduit 46 is connected to the outlet 9 from the machine to subject the motor to the pressure of the pumped medium.

The movement of the motor piston 32 is controlled by throttling valves for controlling movement in either direction. To this end, an adjustable needle valve 47 is provided in an extension 40a of the conduit 40 beyond the connecting conduit 41 which limits the rate of flow of fluid into and out of the end of the cylinder below the piston 32 as viewed in FIGURE 3. Another adjustable bleed valve 48 is connected to the conduit 39 to bleed motive fluid from the line above the piston 32.

Piston valve 43 is yieldingly held in its lowermost open position illustrated in FIGURE 3 by a spring 49 and is moved to its closed shut off position by a solenoid 50 acting on the valve stem 43a. Solenoid 50 is energized by a switch 51 which is opened by a force resulting from an operating condition of the compressor 6 at which surging is apt to occur. In the embodiment illustrated in FIGURE 1 the switch 51 is actuated to open position by a spring 52 and operated to closed position by a current responsive relay coil 53 in the power line P-3. Thus, during stable operating conditions of compressor 6 with a constant load, the switch 51 is held closed by the current responsive relay coil 53 against the action of the spring 52. With switch 51 closed the relay coil 50 is energized from any suitable source of electric current, illustrated diagrammatically at 54 in FIGURE 1, which actuates the piston valve 43 into engagement with the seat 44 to shut off the supply of motive fluid to the motor 30 as shown in FIGURE 2. However, when the load falls off to a value at which surging might occur the spring 52 opens the switch 51. Upon opening of the switch 51, solenoid 50 releases the piston valve 43 which is moved to open position by a spring 49, as shown in FIGURE 3, to bring the anti-surging device 7 into operation. Anti-surging device 7 then controls flow of the medium being pumped to prevent surging.

While a variable current relay coil 53 in the power line P-3 to the motor 10 is illustrated in FIGURE 1 as the control factor for starting and stopping operation of the antisurging device to regulate flow, it will be understood that any other control factor correlated to a surging condition may be used to close or open switch 51. For example, a timer may be used to operate the switch 51 where demand on the blower can be accurately predetermined, or an element which senses the rate of flow of the medium being pumped, or an element that senses the pressure at the outlet from the blower can be used in place of the current relay coil 53 to close or open the switch. While these several control factors, only, are described, it will be understood that any other factor which changes in response to a condition at which surging occurs can also be used. An apparatus incorporating the anti-surging device of the present invention having now been described in detail, the mode of operation is next explained.

When the compressor 6 is operating at a rate above its minimum capacity and is delivering medium being compressed at a substantially constant rate, the operation of the machine is stable and surging will not occur.

5 Under these operating conditions the compressor is doing work on the medium being pumped and the current supplied to driving motor 10 is sufficient to maintain switch 51 closed, see FIGURE 1, the solenoid 50 energized and the piston valve 43 closed. The medium being pumped flowing through the inlet 8 acts on the flaps 12 and 13 of the anti-surging control device 7 to collapse them to the folded back to back relationship at the center of the inlet 8 where they present a minimum and negligible resistance to flow.

10 15 However, when the volume of compressed fluid from the compressor 6 decreases to some minimum rate with a corresponding increase in pressure in the outlet 9, surging or pulsing between the inlet and outlet is apt to occur. The decrease in the work being done also decreases the current supplied to the driving motor 10. This decrease in current flow through the current responsive relay 53 then releases the switch 51 which is actuated to open position by the spring 52, see FIGURE 1. Opening of the switch 51 deenergizes the solenoid 50 so that spring 49 20 moves the piston valve 43 from the position illustrated in FIGURE 2 to that illustrated in FIGURE 3. High pressure fluid from the outlet 9 of the compressor 6 then flows through the line 46 and cylinder housing 42 of piston valve 43, then through conduit 39 into the cylinder 31 of the fluid motor 30 at the top of the piston 32. The high pressure fluid acting on the piston 32 moved it from the position illustrated in FIGURE 2 to that illustrated in FIGURE 3. The downward movement of the piston is initially throttled by the needle valve 47 to 25 prevent oscillation or hunting by the piston.

30 35 Downward movement of the piston 32 of the motor 30 is opposed by the force applied to the vanes 12 and 13 by the medium to be compressed as it flows through the inlet 8 of the machine. Piston 32 operates through the piston rod 33, cross-head 34, links 37 and 38 and arms 25 and 26 to rock the vanes 12 and 13 from the collapsed back to back relation illustrated in FIGURE 2 to an outwardly extended relation tending to close the inlet 8. However, as the vanes move outwardly they present a 40 greater surface area to the impact of the medium being pumped as well as to the difference in pressure at opposite sides of the vanes which opposes their outward movement by the fluid motor 30. Thus, the force opposing extension of the vanes 12 and 13 increases as the load increases, and 45 50 when the force applied to the piston 32 by the fluid from the outlet 9 from the compressor equals the force applied on the vanes by the flow of media through the inlet 8, an equilibrium condition is produced at which the vanes 12 and 13 will be positioned to produce stable flow through the centrifugal compressor 6. With such stable flow no 55 surging will occur. At any time a change in the rate of flow through the inlet 8 occurs the vanes 12 and 13 will move to a new position of equilibrium to maintain stable flow through the machine. Such operation of the centrifugal compressor 6 as controlled by the anti-surging device 7 will continue in the unstable range where surging is 60 normally apt to occur with the vanes 12 and 13 continually adjusting to varying pressure conditions to maintain stable flow.

65 70 75 However, when the flow from the machine 6 increases to a point where any danger of surging is eliminated with a corresponding increase in the load on the compressor, the current flow through the current responsive relay coil 53 increases and closes switch 51 to energize solenoid 50. Energization of the solenoid 50 actuates the piston valve 43 from the position illustrated in FIGURE 3 against the action of the spring 49 to the position shown in FIGURE 2 to shut off the supply of motive fluid to the motor 30. The medium being pumped then acts on the vanes 12 and 13 to rock them back to the collapsed back to back rela-

tionship illustrated in FIGURE 2. Such movement of vanes 12 and 13 is transmitted through the arms 25, 26, links 37, 38, crosshead 34 and piston rod 33 to move the piston. During such movement of the piston 32 the motive fluid including the conduit 39, cylinder 42 of the piston valve 43 and conduits 41 and 40 to the opposite side of the piston to balance the pressure at opposite sides thereof. The compressor 6 will continue to operate so long as stable flow through the compressor exists, but when the load again decreases sufficiently to cause the relay coil 53 to release the switch 51, corresponding to a surging condition, the anti-surging device 7 will again be brought back into operation to actuate the vanes 12 and 13 from their collapsed back to back relation where they produce a negligible resistance to flow to an extended relation to positively resist flow and produce stable operation.

FIGURE 5 illustrates the anti-surging control device 7 of the present invention applied to a centrifugal machine when operating as an exhauster. In this case the control device is applied to the outlet 9 from the machine 6 and its position is reversed so that the vanes move upwardly to a collapsed position and downwardly to an extended position. The valving system is also reversed so as to connect the head end of the motor fluid cylinder 31 to suction pressure in the inlet 8 and operate the vanes 12 and 13 to extended positions to throttle flow. Also, instead of controlling the operation of the anti-surging control device by a current responsive relay coil 53 as shown in FIGURE 1, the device may be controlled by a deflecting vane 60 responsive to flow in inlet 8 to start and stop operation of the device. The pivoted vane 60 is mounted to rock on a shaft 61 and has an eccentric weight 62 projecting from one side of its pivotal axis. Vane 60 in the dotted line position connects the lines L-1 and L-2 of an electric circuit for energizing the solenoid 50 and opens the circuit in all other positions. Thus, when the medium being pumped is flowing through the inlet 8 at a rate to produce a stable operating condition the vane 60 is swung to close the circuit between the lines L-1 and L-2, energize the solenoid 50 and actuate the piston valve 43 as previously explained. However, when the rate of flow is insufficient to maintain the vane in its circuit closing position, at which time a surging condition exists, the eccentric weight rocks the vane to a circuit opening position shown in full lines in FIGURE 5 to deenergize the solenoid 50. The anti-surging device is then brought into action in the manner previously explained to control flow through the outlet and thereby maintain stable operating conditions to prevent surging.

It will now be observed that the present invention provides an anti-surging control device for centrifugal machines which produces a negligible resistance to flow for stable operating conditions and varies the resistance to flow during unstable operating conditions at which surging is apt to occur. It will also be observed that the present invention provides an anti-surging control device which is automatically brought into and out of operation in response to operative conditions. It will also be observed that the present invention provides an anti-surging control device adapted for use with a centrifugal machine whether used as a compressor or an exhauster. It will still further be observed that the anti-surging device of the present invention is of relatively simple and compact construction, economical to manufacture and one which is reliable in operation to perform its intended function.

While several embodiments of the invention are herein illustrated and described it will be understood that further changes may be made in the construction and arrangement of elements without departing from the spirit or scope of the present invention. Therefore, without limitation in this respect, the invention is defined by the following claims.

I claim:

1. An anti-surging control for a centrifugal fluid handling machine such as a compressor and an exhauster

which has an inlet and an outlet passage comprising a butterfly valve in one of the inlet and outlet passages, said valve having separate vanes hingedly mounted for rocking movement on a common axis, the flow of fluid acting on the vanes of said valve tending to move them to a collapsed back to back relationship in the passage in which they are located to produce only a minimum resistance to flow, a fluid motor connected to operate said vanes of the valve away from each other to extended relation to throttle flow through the passage, a source of fluid under pressure, conduit means connecting said source of fluid to said motor, a valve in the connection between said source of fluid and said motor, and means operable responsive to a condition at which surging is apt to occur for opening the valve to deliver fluid under pressure to said motor.

2. An anti-surging control for a centrifugal fluid handling machine in accordance with claim 1 in which the fluid motor is a cylinder having a reciprocating piston therein, and said valve in the connection between said source of fluid and the motor supplying fluid to one side of said piston when open.

3. An anti-surging control for a centrifugal fluid handling machine in accordance with claim 2 in which an adjustable bleed valve is provided in the connection between the source of fluid and the motor to adjust the fluid force exerted on the fluid motor.

4. An anti-surging control for a centrifugal fluid handling machine in accordance with claim 2 in which an exhaust line is provided from the cylinder at the side of the piston opposite the one to which pressure fluid is supplied, and an adjustable valve in said exhaust connection to control the rate of movement of the piston and dampen oscillations.

5. An anti-surging control for a centrifugal fluid handling machine in accordance with claim 2 in which a loop circuit connects the ends of the cylinder at opposite sides of the piston, said loop circuit including said valve between said source of fluid and said motor, and said valve in one position connecting the source of fluid under pressure to one side of the piston and in its other position connecting the opposite ends of the cylinder to each other to allow quick response of the piston in the fluid motor.

6. An anti-surging control for a centrifugal fluid handling machine in accordance with claim 1 in which one of the vanes is connected to a shaft extending across the passage in which it is located, the other vane being connected to a sleeve surrounding the shaft, one end of said shaft and sleeve projecting outwardly from the passage in which the butterfly valve is located, arms projecting radially from the projecting ends of the shaft and sleeve, respectively, to the opposite side of the shaft from its vane, a reciprocating crosshead operated by the fluid motor, and links connecting the crosshead to the outer ends of the extended arms.

7. An anti-surging control for a centrifugal fluid handling machine in accordance with claim 1 in which the machine is driven by an electric motor, a power line for the driving motor, the means operable responsive to a condition which produces surging is a solenoid for actuating the valve, an electric circuit for the solenoid comprising an electric switch biased to one position, and a magnetic winding in the power line responsive to the current flow therein for actuating the switch to its other position.

8. An anti-surging control for a centrifugal fluid handling machine in accordance with claim 1 in which the means responsive to a condition at which surging is apt to occur comprises a vane pivotally mounted in one of the passages to and from the machine, an eccentric weight normally biasing the vane toward one position, the flow of fluid through said port acting on the vane against the action of the weight to bias the switch to

its other position, and an electric circuit for actuating said valve and controlled by said switch.

9. An anti-surge control for a centrifugal fluid handling machine in accordance with claim 1 which operates as a blower, said butterfly valve being located in the 5 inlet passage to control the flow therethrough, and said source of fluid under pressure being fluid from the outlet passage from the compressor.

10. An anti-surge control for a centrifugal fluid handling machine in accordance with claim 1 which operates as an exhauster, said butterfly valve being located in the 10 outlet passage, the source of pressure being the pressure produced in the inlet passage and connected to the cylinder of the fluid motor.
